UNITED STATES PATENT OFFICE.

JAMES W. LYNCH, OF EAST ST. LOUIS, ILLINOIS, ASSIGNEE TO OBEAR-NESTER GLASS COMPANY, OF ST. LOUIS, MISSOURI, A CORPORATION OF MISSOURI.

BOTTLE-BLOWING MACHINE.

1,232,703.

Specification of Letters Patent. Patented July 10, 1917.

Application filed June 26, 1916. Serial No. 105,808.

To all whom it may concern:

Be it known that I, JAMES W. LYNCH, a citizen of the United States, and a resident of the city of East St. Louis, in the county of St. Clair and State of Illinois, have invented a new and useful Improvement in Bottle-Blowing Machines, of which the following is a specification.

This invention relates to glass molding machines, and particularly to machines for blowing glass bottles, wherein the partly formed bottle blank is held in a mold and blown to its proper size.

The object of the invention is to provide a device which will enable the operator to position rapidly and accurately the bottle blank in the mold. A further object of the invention is to prevent the breaking of the bottle blanks and wearing of the molds caused by striking the sides of the molds.

The invention consists in means for positioning the bottle blanks centrally in the molds, and thereby to reduce the liability of breakage of the bottle and wear on the molds.

The invention further consists in a rotating table for the molds, and a swinging support or hanger for receiving the neck of a bottle and suspending it in position to be grasped by the molds, which are successively brought into position by the intermittent rotation of the table. It also consists in the arrangement of parts for bringing the hanger arm back into position after leaving the bottle blank. It also consists in the parts and arrangements hereinafter more fully described and claimed.

In the accompanying drawing, which forms part of this specification and wherein like numerals refer to like parts in the several views,

Figure 1 is a fragmentary plan view of a molding machine, showing one of the molds in open position and the bottle blank in position on the hanger arm;

Fig. 2 is a fragmentary plan view of the same in moved position, the mold being closed and the hanger about to return to its normal position; and

Fig. 3 is a vertical section through the machine on the line 3—3 of Fig. 1.

The device shown in the drawings comprises a frame 1, which has a vertical column 2 upon which is mounted a table 3

which is arranged to turn around the column. A number of molds 4 are fastened at intervals around the table and are opened and closed by handles 5, which are also used to turn the table to bring the next mold into position.

Mounted on the vertical column 2 is a cross-arm 6, which projects out over the tops of the molds. The cross-arm is adjustable vertically so as to clear the tops of molds of different heights and is held in position by a pinch bolt 7. The cross-arm has a vertical slot 8 in its outer end which receives an adjustable pivot bolt 9 on which is pivoted a thin spring steel hanger plate 10. The pivot bolt has a head 11 on its lower end which supports the hanger plate clear of the tops of the molds in normal position, and at the same time leaves it free to pivot. The pivot bolt on which the hanger plate is mounted may be adjusted radially in the slot 8 to accommodate different size molds, and is locked in position by a lock nut 12. The hanger plate projects over the top of the mold which is ready to receive the bottle blank, and has a notch 13 at its front edge which is shaped to embrace the neck of the bottle blank 14 for suspending it in correct position to be grasped by the sides of the mold.

The weight of the bottle blank bends the hanger plate down until it rests upon the top of the mold. The rotation of the table and mold swings the hanger plate laterally far enough to permit the neck of the bottle blank to disengage itself from the notch 13. A spring 15 is provided for returning the hanger plate into position to receive the bottle blank for the next mold. One end of the spring is fastened to a pin projecting down from the hanger plate and the other end is fastened to a pin on the under side of the cross-arm. The cross-arm has a stop pin 16 on its under side which stops and holds the hanger plate in the proper position.

In the operation of the device, the table 100 upon which the molds are mounted is turned intermittently, and the open molds are brought successively into position to receive the bottle blank. The neck of the bottle blank is then placed in the notch in the 105 hanger plate and the mold is closed. The table is then turned, whereupon the hanger plate swings on its pivot, and the neck of

the bottle blank is carried out of the notch in the hanger plate. The spring then returns the hanger plate to its normal position against the stop pin, ready to receive 5 the next bottle blank.

Heretofore the bottle blanks have been inserted in position by hand and the unavoidable inaccuracy in positioning the bottle blank in the mold has caused the bottle blank 10 to break and the molds to rapidly become worn. It can be readily seen from the foregoing description that my device increases the output of the machine and causes a great saving in bottle blanks and molds.

15 What I claim as my invention is:

1. A positioning device for bottle molding machines comprising a horizontal cross-arm located above and extending in the direction of the molds, a spring hanger plate pivotally secured to the under face of said cross-arm, said hanger plate extending above and across the top of the mold and provided with a notch in its front edge to receive the neck 20 of a bottle blank and position it centrally in 25 the mold, and means for normally retaining

said spring hanger plate with its notch centrally over said mold.

2. A molding machine comprising a frame, a mold carrier supported thereby, said carrier being rotatable around a vertical axis, molds on said carrier, and vertically yieldable means on said frame for cushioning bottle blanks and positioning them in the molds, said means being operated by the weight of the bottle blanks and rotation of 30 35 said carrier and bottle blank.

3. A positioning device for bottle molding machines comprising a horizontal cross-arm, a pivot on said cross-arm, a spring metal hanger plate pivoted for horizontal movement on said pivot, a notch in said hanger plate to embrace the neck of the bottle, said hanger plate being adapted to deflect under the weight of the bottle and to swing on said pivot for allowing the bottle to be carried 40 45 out of the notch, and means for returning the hanger plate to its normal position.

Signed at St. Louis, Missouri, this 24th day of June, 1916.

JAMES W. LYNCH.
